No. 851,198.

PATENTED APR. 23, 1907.

J. M. DIETZ, C. W. ANDERSEN & J. W. FARRELL.
ATTACHMENT FOR HOT AIR REGISTERS.

APPLICATION FILED FEB. 12, 1901.

UNITED STATES PATENT OFFICE.

JOHN M. DIETZ, CARL W. ANDERSEN, AND JOHN W. FARRAR, OF SALT LAKE CITY, UTAH.

ATTACHMENT FOR HOT-AIR REGISTERS.

No. 851,198.

Specification of Letters Patent.

Patented April 23, 1907.

Application filed February 12, 1901. Serial No. 47,045.

To all whom it may concern:

Be it known that we, JOHN M. DIETZ, CARL W. ANDERSEN, and JOHN W. FARRELL, citizens of the United States, residing at Salt Lake City, in the county of Salt Lake and State of Utah, have invented certain new and useful Improvements in an Attachment for Hot-Air Registers; and we do hereby declare the following to be a full, clear, and exact description of the invention, such as will enable others skilled in the art to which it appertains to make and use the same.

This invention relates to an attachment for hot air registers.

15 The object of the present invention is to provide an attachment for the register by which the cold air in the room is prevented from entering the register flue and the hot air escaping therefrom is caused to be deflected downward toward the floor.

20 A further object is to provide the attachment with a device for separating the dust, soot or other impediments from the hot air as it escapes from the register and to provide 25 means by which the slats may be operated from the exterior of the attachment.

The invention embodies a rectangular casing adapted to be fitted to the register and project from the face plate thereof into the 30 room, the top of said casing being bent downward to deflect the heat toward the floor, a screen pivoted in the casing and adapted to be turned up under the deflector or down beneath the same and an operating rod for the 35 slats extending through the side of the casing.

35 The invention is illustrated in the accompanying drawings in which:—

Figure 1 is a perspective view of our improved register as it appears in use. Fig. 2 40 is a vertical section of the same. Fig. 3 is a transverse section on the line $x-x$ of Fig. 2 looking in the direction of the arrow.

45 Referring to the drawings 1 designates the wall of the building against which the face plate A of the register is placed. In the wall is an opening in which is fitted a casing a containing the pivotal slats a'.

50 Our improvement consists of a sheet metal casing B having its inner edges bent inwardly as at b to be clamped between the face plate A and the wall of the building. This casing B envelopes the sides and ends of the face plate A and extends outwardly therefrom into the room, its outer longitudinal side edges being

inclined so that its base is of less depth than 55 its top. The top of the casing is curved outwardly and downwardly to form a deflector b' by means of which the heat is given a downward course as it escapes from the register.

60 Mounted in the deflector b' is a screen C having the segmental end plates c and c' braced and held together by the rods c' spaced apart along these curved edges of the end plates. The curved edges of the segments coincide with the curved inner face of the deflector. On the curved edges of the plates is secured a piece of reticulated material d which catches or arrests dust, soot, or other foreign matter which might escape 70 through the register.

75 The screen stands normally, and automatically, across the casing with its outer edge portion lapped over the lower edge portion of the deflector and its inner edge lodged against the face-plate of the register, as indicated in Fig. 2 of the drawings, so as to intercept such descending debris as may accompany the discharging current.

80 The plates c and c' are secured to a rod e having an eye e' formed on one end to provide a handle and this rod is pivoted in the sides of the casing beneath the deflector so that when it is rotated by the handle e' which projects beyond the side of the casing the 85 screen will be turned up in the deflector or beneath the same as shown in Figs. 1 and 2. When turned up the deflector may be readily cleaned.

85 To conveniently operate the slats without lifting the screen, we provide an operating rod F having a handle f at one end projecting through one side of the casing and secured at its other end to a stud g of a sliding plate G. This sliding plate G is confined within the 90 casing and engages the ends of the pivotal slat a' and its stud g extends through a slot in the face plate A so that when the operating rod F is pulled the plate will also be pulled to close the slats.

95 As the tendency of hot air is to rise to the highest point possible, the air ascending the flue will naturally seek the highest point thereof, and the greater part in escaping into the room will pass through the upper portion 100 of the face plate, strike the deflector b', and pass downward through the screen, which 105 acts to free it from soot and dust.

With this particular casing the velocity of the hot air is greater than with the usual registers, because it is well known that ordinarily the cold air in a room enters the bottom 5 of the register, takes a downward course, and checks the ascent of hot air shutting off 40% of heat, while in the present invention the bottom and sides of the casing serve as a guard to prevent this; consequently the hot 10 air strikes against the deflector with considerable force and is then deflected toward the floor distributing the heat throughout the room.

Having thus described our invention, we 15 claim:

The combination with a hot-air wall register of an attachment comprising a casing having its inner edges bent inwardly to engage behind the flanges of the face-plate of the 20 register and the body of the casing standing out from the wall and curved downwardly at its upper portion to form a deflector the upper portion of the casing being bulged as

compared with the lower portion thereof and the free edge of the deflector being reinforced 25 to strengthen the said edge of the deflector, a rod pivotally mounted across the upper portion of the casing and one end thereof extending therefrom to form a handle, segmental plates rigidly mounted on the rod at the inner sides of the casing and their curved edges coincident with the curved contour of the deflector, and a metal screen having its ends secured to the curved edges of the segments, 30 said screen standing normally across the casing under the deflector, substantially as shown.

In testimony whereof we affix our signatures, in presence of two witnesses.

JOHN M. DIETZ.
CARL W. ANDERSEN.
JOHN W. FARRELL.

Witnesses:

JOHN F. CORKER,
MARETTA BURNHAM.
